UNITED STATES PATENT OFFICE

JOSEPH HUEBSCH, OF MILWAUKEE, WISCONSIN, ASSIGNOR TO HUEBSCH MFG. CO., OF MILWAUKEE, WISCONSIN, A CORPORATION OF WISCONSIN

UNIVERSAL IRONING MACHINE

Application filed April 24, 1925. Serial No. 25,469.

This invention relates to universal ironing machines and is an improvement on the device of my prior Patent No. 1,623,187, filed February 9, 1924.

5 It has become desirable to provide an improved ironing machine of the type shown in the above mentioned application and it is accordingly an object of this invention to provide an efficient machine of this class.

10 With the above and other objects in view as will be apparent, this invention consists in the construction, arrangement and combination of parts, all as hereinafter more fully described, claimed and illustrated in

15 the accompanying drawings.

On the drawings:

Figure 1 represents an end view of an ironing machine embodying this invention.

Figure 2 represents a side view of the same.

20 Figure 3 represents a plan view of the same.

Figure 4 shows a section along the line 4—4 of Figure 3.

Figure 5 shows a vertical section at the 25 line 5—5 of Figure 3.

Figure 6 is a detail view of the operating mechanism.

Figure 7 is an end detail view of a part of the mechanism for transmitting intermittent motion to the roller.

Figure 8 is a side view of the same.

Figure 9 is an end view of a part of the mechanism shown in Figure 6.

Figure 10 is a detail view of a portion of 35 the mechanism for operating the presser.

Figure 11 is a plan view of the same.

Figure 12 is a view from the right of Figure 11.

As shown on the drawings:

40 Numeral 1 represents a suitable housing for the ironing machine having a removable section 2 rigidly secured thereto. The section 1 is hollowed as shown in Figure 5 and is adapted to support therein a shaft 3 on bearings 4 which are held in place by cap members 5. The shaft 3 is securely held against longitudinal movement in the casing section 2 by means of the shoulders 6. The left hand cap member 5 as viewed in Figure 50 5 is recessed so as not to interfere with nuts

7 which hold the movable portion of the left hand roller bearing 4 against the shoulders 6. The shaft 3 extends exteriorly of the housing section 2 and has mounted thereon on its exterior portion a drum 8. A presser member 9 having an arcuate surface substantially concentric with the surface of the drum 8 is movably supported above said drum and is adapted to be brought into engagement therewith for pressing, as will be hereinafter described. The presser member 9 has rigidly secured thereto a longitudinally extending guard member 10 which is adapted to strike the arm of the operator in case his hand happens to be between the roller 8 and the member 9 when the latter is being lowered. The presser member 9 is suitably supported by longitudinally spaced arms 11 which are pivoted on a shaft 12 within the housing 1, the housing 1 being apertured as at 13 for this purpose. The surface of the housing 1 has a cylindrical shape adjacent the aperture 13, said shape being concentric with the shaft 12. A sleeve member 14 is provided for closing said apertures 13 at all times and is rigidly secured to the arms 11 exteriorly of said apertures 13 and is also of a shape concentric with the shaft 12. The arms 11 extend rearwardly in the casing 1 and are pivotally connected as at 15 to a collar member 16. The 55 collar member 16 receives slidably therein a rod 17. Said rod 17 has thereon a second collar member 18 relatively movable therewith along the length thereof and a pair of nuts 19 which are adapted to hold said collar 18 securely in upward position on said rod 17. A spring 20 surrounds the rod 17 and is adapted to be abutted by the collar members 16 and 18. The rod 17 threadedly engages in a clamp member 20^a which is 60 pivoted as at 21 to a safety dog 22, a link 23 and a connecting rod 24 having a slot 25 therein. The link 23 is pivoted as at 26 to a bracket 27 rigidly secured to the housing 1 and form a toggle with rod 17. The safety 65 dog 22 is hookshaped substantially as shown and is adapted to engage over a rod 28 rigidly secured to the inside of the housing 1 when the presser member 9 is in upward position and the mechanism just described is in 70 75 80 85 90 95 100

a dotted line position as shown in Figure 10. The connecting rod 24 has thereon a lug 31 which is adapted to engage with a lug 32 on the dog 22 when the presser member 9 is 5 near its low position. A crank 33 on a shaft 34 which rotates anti-clockwise and which is suitably supported in the housing 1 on roller bearings 35 is adapted when in the position shown in Figure 4 to force the dog 22 by 10 reason of the lug 31 and 32 rearwardly for straightening the toggle and pressing the presser member 9 firmly against the drum 8. As shown in Figure 11, the rod 28 is provided at its ends with bosses 29 which are 15 slidably mounted in a suitable casting and which may be adjusted by the set screws 30. It is therefore possible to adjust the rod 28 so that the dog 22 will not drop therefrom until the presser member 9 is in a satisfactory 20 and safe relation to roller 8. The mechanism for controlling the movement of the crank 33 will now be described. The shaft 34 has rigidly secured thereon a frictional clutch housing 36. A shaft 34^a axially 25 aligned with the shaft 34 and movable relatively therewith is supported to the left of said shaft 34 as shown in Figure 5 by means of roller bearings 36^a in the casing 1 and has keyed thereon a conical clutch member 37. A collar member 38 is loosely mounted 30 on the shaft 34^a and by means of a lever 39 pivoted on the shaft 40 and connected to an operating lever 41 by means of lever 39^a rigidly secured on said shaft 40 and rod 39^b 35 is adapted to abut a spring 42 for forcing the clutch member 37 into clutching engagement with the member 36 on the shaft 34. The shaft 40 oscillates with the lever 39 and has rigidly secured thereon a lever 43 which 40 extends therefrom normally to the lever 39. A spring 44 secured with one end to the casting 1 and the other end to the outer end of the lever 43 is in line with the lever 43 when the same is substantially intermediate of its 45 extreme arc of movement such that said spring 44 will act to throw the collar member 38 out of clutching engagement or in clutching engagement depending upon whether or not lever 43 is below or above, respectively, 50 its central point of movement. A pair of lugs 45 (Fig. 6) diametrically positioned on the clutch housing 36 are in line with the crank 33 (Fig. 6) when the latter is in position for pressing the presser member down, as shown 55 in Figure 4. A dog 46 held in the position on the collar member 38 and pivoted thereto as shown in Figure 6 is adapted to be abutted by the lugs 45 when the presser member 9 is in downward pressed position for throwing 60 the collar member 38 to the left as shown in Figure 6 to release the clutch members 37 and 36, thus preventing the crank from releasing its pressure on the presser member 9. A brake band 47 surrounding the clutch 65 housing 36 is connected by means of the rods 48 and 49 and link 50 to the lever 43 and is adapted to frictionally engage said housing 36 and hold the crank shaft 34 in position when the clutch member 37 is released from clutching engagement with said housing 36. It will be noted that when the lug 45 strikes the lug 46, the lever 39 and shaft 40 will be given a partial rotation. Consequently the lever 43 on the shaft 40 will be actuated for applying the brake when the clutch is 70 thrown out. When it is desired to raise the presser member 9 it is necessary to throw the lever 41 in position for again engaging the clutch members 37 and 36. The resilient mounting of the dog 46 enables it to be forced into position over the lugs for permitting clutch members 37 and 36 to again engage to further rotate crank 33 to raise the presser member. The mechanism for controlling the continuous and intermittent rotation of the drum 8 is similar to that of my above mentioned prior application and will now be described. 75

A worm wheel 51 is secured on the shaft 34^a and is adapted to be driven by a worm 52 on a motor shaft 53 of a motor 54 supported in the housing 1. A pair of pinions 55 and 56 are loosely mounted on shaft 34^a and are provided with jaw clutches upon their adjacent faces. A clutch member 57 is slidably splined upon the shaft 34^a between the pinions 55 and 56. This clutch is adapted to be actuated by a yoke lever 58 secured upon a shaft 59. The shaft 59 is suitably connected to an operating lever 60 for actuating the same to throw the clutch 57 into engagement with the pinion 55 or 56 as may be desired. A shaft 61 is rotatably supported on roller bearings 62 in the casing 1, said shaft 61 being parallel to shaft 34^a. Keyed on the shaft 61 is a gear wheel 63 which engages with the pinion 55. A sprocket wheel 64 is also keyed to the shaft 61 and is adapted to continuously drive the roller shaft 3 by means of sprocket wheel 65 thereon and chain 66 when the lever 60 is actuated to throw the clutch 57 into engagement with the pinion 55. A second gear 67 is loosely mounted on the shaft 61 and is adapted to engage with the pinion 56 of the shaft 34^a. A ratchet wheel 68 is secured upon the shaft 61 and is adapted to be engaged by a pawl 69 (Figure 7) pivoted upon the gear 67. A spring 70 connected with the free end of the pawl 69 and the gear 67 normally tends to withdraw the pawl from engagement with the ratchet wheel. A compression spring 71 extends from the pawl 69 for engaging under an arcuate guard 72, which is slidably mounted upon rods 73 and 73^a for pressing the pawl into engagement with the ratchet wheel. 100

It will be evident that as long as the end of the spring 71 which is provided with a bevelled head engages under the arcuate guard 72, the pawl will be held in engagement with 105

110

115

120

125

130

the ratchet wheel 68 for rotating the shafts 61 and consequently the roller shaft 3. However, when the pawl rides out from under the arcuate guard 72 the spring 70 will withdraw the pawl from the ratchet wheel 68 thereby preventing further rotation of the shafts 61 and 3. The guard 72 is connected to the shaft 59 by a link 74. The gear 67 is provided with a cam 75 extending laterally from the side 10 thereof. This cam is adapted for engaging against the side of the arcuate guard 72 and shifting it laterally upon the rods 73 and 73^a for moving the same out of the path of the pawl 69 and simultaneously rotating the shaft 15 59 through the link 74 for shifting the clutch 57 to neutral position for stopping the rotation of the gear 67. The arcuate guard 72 has the same angularity of arc as the arcuate 20 surface of the pressing member 9 so that the circumferential movement of the ironing roller 8 will equal the arcuate extent of the pressing member 9. The arcuate guard 72 is adapted to be manually shifted by the crank 25 60 when said crank is actuated to reengage the clutch member 57 with the pinion 56. A counterweight 76 is secured upon the lower end of a cable 77 attached thereby to a peg on the gear 67. This counterweight is suitably guided by rollers 78 secured to the casing. 30 This counterweight is adapted to return the gear 67 after each actuation to its initial starting position with the pawl 69 under the upper end of the arcuate guard 72 as shown in Figure 7. Lever 58 is suitably connected 35 through lever 58^a and rod 58^b to the operating lever 60 for actuating the same to throw clutch 57 into engagement with the pinion 55 or 56 as may be desired.

A pair of brackets 79 extend from the casting 1 for supporting an ironing board 80 below the roller 8 upon which a certain amount of hand ironing may be done.

The operation of the machine will now be described. Let it be assumed that it is desired to iron articles which require merely a rolling action. The lever 60 will be thrown into position connecting the pinion 55 with the clutch member 57 so that the shaft 34^a driven by the member 54 through the worm 52 and worm wheel 51 will drive the roller shaft 3 through the gears 63, sprocket wheels 64, chain 66 and sprocket wheel 65 on said roller shaft 3. The lever 41 will then be thrown into position for engaging the clutch members 36 and 37 and the presser member 9 will be lowered by gravity, the clutches 36 and 37 engage, causing the slotted connecting rod 24 to move rearwardly so that the pivot point 21 also moves rearwardly by the weight of the presser member 9 though controlled by rod 24. The lug 31 on the connecting rod 24 will engage with the lug 32 of the dog 22 when the presser member 9 is in almost lowered position and when the crank 33 reaches the position shown in Figure 4 said presser member

9 will be firmly but resiliently held in downward position against the roller 8 by means of the spring 20. When the crank 33 has reached the position shown in Figure 4 with the presser member 9 in downward pressed position, lugs 45 on the clutch member 36 will have disengaged the clutch member 37 by abutting the dog 46, and the lever 43 through means of the brake band 47 connected thereto will prevent the clutch member 36 and crank 33 from over running so that presser member 9 will continue to be held in the downward position. When an article has been passed between the roller 8 and the presser member 9, another may be inserted without stopping the machine so that a continuous rolling or ironing action results. The guard 10 is also adapted to act as a feed board for flat pieces, such as handkerchiefs, etc. When it is desired to stop the machine or raise the presser member 9, it is only necessary to actuate the levers 60 or 41 respectively.

It will be appreciated that when the presser member or buck 9 is in elevated position, the parts are in the dotted line position as shown in Figure 10. In this position, the safety dog 22 is supported upon the rod 28. Now as the buck 9 is lowered, it is obvious that the safety dog will gradually slide off the rod 28. If something should get under the descending buck, such as the operator's fingers, the dog 22 would not ride off the rod 28, with the result, that if the motor should be running, no pressure would be applied to the toggle due to the slotted link and the fact that the shoulders 31 and 32 are at such time not in coacting relation; it is necessary for the dog 22 to slide completely from the rod 28 and drop down as shown in Figure 4 before the shoulder 31 on the slotted link can engage the shoulder 32 on the dog for applying pressure to the toggle 18-23 for straightening the same and applying pressure upon the buck.

Now let us assume it is desired to press certain classes of garments or articles which cannot be readily ironed by a continuous rolling action, but require an intermittent action. Assuming that the presser member 9 is in elevated position and the lever 60 and clutch 57 connected thereto are in neutral position as shown in Figure 6, the garment or articles to be pressed may then be inserted between the roller 8 and the pressing member 9. When the garment has been properly positioned, the lever 41 may be actuated to engage the clutch members 36 and 37. The presser member 9 may be lowered by actuating the lever 41, and said presser member 9 will then be firmly but resiliently forced against the garment or article on the roller 8 as heretofore described. The presser member 9 is then raised by again actuating the lever 41 as heretofore described. The roller 8 may then be rotated a distance equal

to the arcuate surface of the presser member 9 by actuating the lever 60 in the reversed direction for engaging the clutch member 57 with the pinion 56. When the clutch member 57 engages with the pinion 56 the pawl 69 will be in the position shown in Figure 7 except that the arcuate guard 72 will be engaging with the spring 71 for causing the pawl 69 to engage with the ratchet wheel 68. 5 When the gear 67 has rotated sufficiently so that the spring 71 rides off the arcuate guard 72, the pawl 69 will disengage from the ratchet 68 and before it can again reach the arc 72 for again engaging the ratchet 68 the cam 15 75 will have engaged with the guard 72 and shifted it laterally to disengage the clutch 57 from the pinion 56 so that the roller 8 will only move enough to present a new surface beneath the presser member 9. The counter- 20 weight 76 will always return the gear wheel 67 to initial starting position as shown in Figure 7 so that when the lever 60 is again actuated to engage the clutch member 57 with the pinion 56, the roller 8 may again 25 be rotated so as to remove the pressed portion beyond the confinement of the presser member 9 to bring any non-pressed portion to juxtaposition with respect to the presser member 9. The roller however may be 30 stopped at any time when pleats or ruffles are encountered by simply throwing the clutch member 57 into neutral in the position shown in Figure 6. From the foregoing it will be evident that this ironing machine 35 may iron garments by rolling action or simply by pressing action in which the pressed article may be advanced a predetermined distance. Accordingly, any kind of garment or piece of fabric may be ironed in the 40 machine.

I am aware that many changes may be made, and numerous details of construction may be varied through a wide range without departing from the principles of this 45 invention, and I therefore do not purpose limiting the patent granted hereon, otherwise than necessitated by the prior art.

I claim as my invention:

1. In an ironing machine, a roller, a movable pressing member adapted for cooperating with said roller, operating mechanism for said movable pressing member including a pair of coacting members adapted for coming into coacting relation when said pressing 50 member and roller are in substantially contacting relation, and a stationary support for normally maintaining one of said members out of coacting relation with the other member, said one member riding off said support during the descending movement of said pressing member.

2. In an ironing machine, a frame, a roll, a pressing member engageable with said roll, a lever pivoted intermediate its ends for carrying said pressing member, a toggle con-

nected at one end to the frame and at the other end to said pressing lever, a safety dog carried by said toggle, a stationary support for normally sustaining said dog, and power operated means for operating said toggle and causing relative movement between said dog and the stationary support, said dog riding off said support when said toggle is substantially straight and cooperating with said power means for applying the final pressure to said pressing member. 70 75

3. In an ironing machine, a pressing member, a movable buck cooperating with said pressing member, a lever for carrying said buck, a toggle for actuating said lever, a dog carried by said toggle, a slotted link, said toggle passing through the slot in said link, a stationary support for normally holding said dog out of the path of movement of said slotted link, and power operated means connected to said link for operating said toggle, said dog being movable on and off said support during the movement of the toggle and said dog and said slotted link having coacting parts adapted for coming into coacting relation when said buck and pressing member are in substantially contacting relation. 80 85 90

4. In an ironing machine, a frame, a movable pressing member, a toggle mechanism connected at one end to said frame and having a connection at its other end with said movable pressing member, a power operated device and a lost motion connection between said device and toggle, said connection serving to break the toggle when moving in one direction and running idly a predetermined distance when moving in the other direction, a member carried by said toggle for coaction with said slotted link when said pressing member has been lowered a predetermined extent and means for controlling the movement of said member. 95 100 105

5. In an ironing machine, a stationary pressing member, a movable pressing member, a toggle connected to said movable member, driving mechanism for said toggle including a pair of members having an inoperative relation when said movable member is elevated and adapted to be brought into operative relation when said movable member has descended one of said members comprising a safety dog and means for holding said dog out of the path of the other member until the movable member has descended. 110

6. In an ironing machine, a stationary pressing member, a movable pressing member, a toggle connected to said movable pressing member, a safety dog carried by said toggle, a slotted link connected to said toggle, said link and dog having coacting abutments, means for moving said dog out of the path of said slotted link during the elevating movement of said movable member and for moving said dog into the path of the abutment on said link when said movable mem-

- ber has been lowered a predetermined distance.
7. In an ironing machine, a pressing member, a toggle connected to said member, a link having a lost motion connection with said toggle, power operated means connected to said link for breaking said toggle when moving in one direction and cooperating means on said link and toggle for straightening said toggle and applying the final pressure to said member when moving in the other direction; a part of said cooperating means being movable into and out of the path of said link. 10
8. In an ironing machine, a movable pressing member, a toggle connected to said member, driving mechanism for actuating said toggle for elevating said pressing member, a dog carried by said toggle for coaction with said driving mechanism, a stationary support over which said dog moves during the flexing of the toggle, said support being adjustable for causing said dog to clear said support when said pressing member has been lowered 20 for coaction with said driving mechanism. 25
9. In an ironing machine, a gravity lowered pressing member, driving mechanism for elevating said member, said driving mechanism embodying a clutch and a brake, and means for automatically and simultaneously disconnecting said clutch and applying said brake when said pressing member is in lowered position. 30
10. In an ironing machine, a stationary ironing member, a movable pressing member, a toggle connected to said movable member, a crank shaft connected to said toggle, a clutch member on said shaft, driving mechanism embodying a movable clutch member for engaging said first mentioned clutch member, manually operated means for shifting said movable clutch member, a brake for said crank shaft and means on said first mentioned clutch member for automatically disconnecting said movable clutch member and applying said brake when said pressing member is in a predetermined position. 35
11. In an ironing machine, the combination with a pressing element, of a member engageable therewith by a descending movement for pressing an article therebetween, a crank connected to said member, driving means connected to said crank, means for disconnecting said driving means when said member is in lowered position, said disconnecting means comprising a pair of clutch members, manually operable means for controlling said clutch members, means associated with one clutch member for automatically reTRACTING said manually operable means and braking means for said crank controlled by said manually operable means. 40
12. In an ironing machine, a stationary pressing member, a movable buck for operating therewith, toggle mechanism con-
- nected to said buck, driving mechanism for operating said toggle including a slotted member connected to said toggle, a device carried by said toggle mechanism, said device and slotted member having coacting parts adapted to come into cooperative relation when said buck has been lowered a predetermined extent and means for maintaining said device out of such cooperative relation until said buck has been lowered such a predetermined extent. 70
13. In an ironing machine, a stationary pressing member, a movable buck for operating therewith, a toggle connected to said buck, driving mechanism for said toggle including a lost motion connection together with a member movable with said buck and movable into the path of said connection when said buck has been lowered a predetermined extent. 80
14. In an ironing machine, a stationary pressing member, a movable buck for operating therewith, a toggle connected to said buck, mechanism for operating said toggle including a lost motion link connected to said toggle and a safety dog movable with said buck and movable into the path of said link when said buck has been lowered. 85
15. In an ironing machine, a stationary pressing member, a movable pressing member cooperating therewith, a toggle connected to said movable member, operating mechanism for said toggle including a lost motion connection serving to break said toggle when moving in one direction and for elevating said movable member and running idly a predetermined extent when moving in the other direction, and coacting means on said connection and toggle adapted to come into operative relation for straightening said toggle when said buck has descended. 90
16. In an ironing machine, a movable pressing member, a toggle connected to said member, power operated means including a lost motion connection for breaking said toggle when said connection is moving in one direction, a movable device responsive to the movements of said pressing member and carried by said toggle for moving into cooperative relation with said lost motion connection when said pressing member has been moved to operative position and means for maintaining said device out of such cooperative relation until said member has been moved to operative position. 100
17. In an ironing machine, a stationary pressing member, a movable pressing member adapted for cooperation with said first member, a toggle connected to said movable member, a power operated device, a lost motion connection between said toggle and device serving to break said toggle when said connection is moving in one direction, an element adapted for cooperation with said connection for straightening said toggle when said connection is moving in one direction. 115
18. In an ironing machine, a stationary pressing member, a movable buck for operating therewith, toggle mechanism con-

nection is moving in the other direction, and means for maintaining said element out of such cooperative relation until said members are in substantially contacting relation.

5 In testimony whereof I have hereunto subscribed my name.

JOSEPH HUEBSCH.

10**15****20****25****30****35****40****45****50****55****60**
